UNITED STATES PATENT OFFICE.

FREDERICK C. WHITMORE, OF NEW YORK, N. Y., ASSIGNOR TO DISPLAY VENDING CO.,
A CORPORATION OF NEW YORK.

VENDING-MACHINE.

1,075,527.

Specification of Letters Patent.

Patented Oct. 14, 1913.

Application filed December 18, 1911. Serial No. 666,318.

To all whom it may concern:

Be it known that I, FREDERICK C. WHITMORE, a citizen of the United States, and a resident of the city, county, and State of New York, (whose post-office address is No. 112 West One Hundred and Forty-fourth street, New York city, New York,) have invented a new and useful Improvement in Vending-Machines, which invention is fully set forth in the following specification.

My invention relates to coin-controlled vending-machines, particularly of the class where there is a plurality of compartments that may contain different kinds of goods, with means for bringing any one compartment into position for delivery. But the invention is applicable to other forms of vending-machines.

The invention comprises a "package-chute" in which is stacked a vertical pile of chewing-gum, candy, matches, or other goods to be vended, with coin-controlled means for ejecting the lowermost package.

My invention relates principally to the coin-controlled ejecting means, and comprises various features of construction and arrangement in connection therewith.

My invention will be best understood by reference to the accompanying drawings, that illustrate a preferred embodiment thereof.

In these drawings—Figure 1 is a vertical section through one form of vending apparatus employing my invention, taken 35 through the line I—I of Fig. 2; Fig. 2 is a transverse section through Fig. 1; Fig. 3 is a vertical section, on a larger scale, of the coin-controlled ejector, with certain adjacent parts; Fig. 4 is a plan view, partly 40 broken away, of the same; Fig. 5 is an end view of a detail, viewed from the right, through the line V—V of Fig. 3; Fig. 6 is a longitudinal sectional view, viewed from the center of Fig. 4, showing the plunger in 45 its outer position; Fig. 7 is a similar view, to one side of the view shown in Fig. 6, and showing the plunger in its inner position; Fig. 8 is a section of another detail of the ejector; Fig. 9 is a perspective view of the 50 turntable for supporting the package-chutes; and Figs. 10 and 11 are a vertical section and a plan respectively, of a modification of details shown in Figs. 6 and 7.

Referring to Figs. 1 and 2, 1 is the base portion and 2 the upper portion of the main

casing, shown as broken away through the center; and at 3 are glass windows. The vertical shaft 4 is journaled in the bottom and top of the casing, and carries the spider 5 which serves as a turntable for supporting 60 the package-chutes 6. 7 is a large beveled gear fast at the lower end of shaft 4, and 8 is a smaller beveled gear in mesh therewith and carried on a horizontal shaft 9 that extends outside of the casing and carries the 65 hand-wheel 10. 11 is the delivery-chute, whose upper end terminates just below the spider 5. By rotating handle 10, shaft 4 and its package-chutes are rotated, so as to bring any desired pile of packages above 70 the delivery-chute. The windows 3 permit inspection of the contents of the package-chutes 6. On the shaft 9 is shown a star-wheel 12, with which cooperates a pawl 13, for holding the spider and package-chutes 75 stationary in any desired position. 14 represents conventionally a vertical pile of packages located in one of the package-chutes 6. 15 designates a plunger that, by being pushed in, pushes the bottom package 80 14' inward until it falls through the delivery-chute 11. The spider 5 (see Fig. 9) comprises what I may designate as an outer "stepped ring" consisting of portions 16 constituting an upper level and portions 17 85 constituting a lower level connected by the vertical portions 18. 19 are notches in the outer edges of the lower level 17. The package-chutes 6 are mounted above the seats provided by the lower level 17, the width of 90 each chute being somewhat greater than said seats, so that the lowermost package 14' in each chute rests with its ends upon the shoulders thus provided by the portions 16. The rear wall of each package-chute is cut away 95 at its lower end, in order that the lowermost package 14' may have access into the delivery-chute 11, into which it is to be pushed by the plunger 15.

In the preferred form of my invention, 100 the lower portion 1 of the main cabinet is provided with a slide-way 20, above which is located a block 21 for carrying various devices co-acting with plunger 15, which latter slides between the slide-way 20 and this 105 block (see Figs. 3 to 8). This plunger is adapted to receive the coin, and cannot be operated without the proper coin, as will be described below. At 22, near the rear of plunger 15, is pivoted an inclined plate 23, 110

having at its inner end the down-turned arms 24—24 to form the abutment for ejecting the package 14'. A spring 25 normally holds the ejector in the elevated position shown in Fig. 3; but when the lowermost package has been ejected, the pile of remaining packages drops down upon the shoulders 16—16, thus collapsing the spring-pressed ejector 23, so that the plate 23 is collapsed and the plunger 15 can be readily withdrawn. Although the star-wheel 12 with its catch 13, already described, may suffice to hold the turntable stationary, yet it is sometimes desirable to provide additional means for this purpose. To that end, I pivot arm 26 in such position that its nose can drop into one of the notches 19 in the spider disposed beneath the package-chute in position for delivery; while a spring 27 normally holds this arm in the elevated position shown in Fig. 3. When the hand-wheel 10 has brought the desired pile of goods into proper position, and as the plunger 15 is forced inward, the inner end of the plunger 25 forces this arm 26 into engagement with notch 19 in advance of the spring-pressed ejector, so that when the latter enters its sphere of action there is no danger of its being interfered with by any accidental swinging of the turntable.

Referring now to the coin-controlled devices proper, illustrated in Figs. 3 to 8, the plunger 15 is shown as a flat plate adapted to slide in and out of the guide-way 20 and beneath the block 21. At 30 is a circular hole through this plate, adapted to receive the proper coin. The diameter of this hole 30 and the thickness of the plunger 15 are calibrated carefully with respect to the coin 40 for which the apparatus is intended. In a longitudinal slot in the block 21 is pivoted the dog 31, having on its outer arm two projections that will be referred to respectively as toe 32 and heel 33, while a spring 34 tends 45 to elevate the inner arm, and thereby forces the toe and heel of this dog into contact with the plunger 15 (see dotted lines in Fig. 3). In the plunger 15, at the rear of coin-hole 30, is an opening 35 adapted to receive the heel 33,—the parts being so located that the heel is in position to drop into this hole at the same instant that toe 32 clears the rim of the coin-hole 30. If there be no coin in this hole 30, or if the coin be either too 50 thick or too thin, the dog 31 locks the plunger 15 against being pushed rearwardly; if there be no coin, or if the coin be too thin, the toe 32 will drop into the position indicated in Fig. 6, and at the same time the heel 55 33 will drop into this hole 35, thus locking the plunger against further advance; whereas, if the coin be too thick, the toe 32 will abut against its upper edge and lock further advance of the plunger and coin. In the 60 same block 21 is pivoted a double-ended

dog 40, both of the arms 41 and 42 of which normally rest upon the upper surface of the plunger 15. On this plunger is located the tripping-cam 43, in alinement with the end of arm 42, the parts being so positioned that this cam 43 will trip the rear arm 42 when the coin-hole has reached the front arm 41. In this position (see Fig. 7) the front arm 41 is forced down into the hole, and would push the coin out of the plunger. In the 70 same block 21 is pivoted a pawl 50, as shown in Fig. 8, which figure is reversed with respect to the other figures of the sheet, whose free end co-acts with a rack 51 on the plunger 15. At each end of this rack the plunger 15 has a hole 52 and 53. The parts are so proportioned, and the distance between the two holes 52 and 53 is such, that when the plunger is in its outermost position this pawl drops into the rearmost hole 52, and when the plunger is in its innermost position the pawl drops into the outer hole 53. In intermediate positions, the pawl is trailing, so that the plunger cannot be "pumped" 80 back and forth, but can only be shoved entirely in and shoved entirely out.

In Figs. 10 and 11 is shown a modification of the coin-ejecting device. This comprises a disk 60 pivoted in the same or a similar block 21, and provided with a rearwardly-extending arm 61, shown in Fig. 11 as offset. The plunger 15 has the same or a similar tripping-cam 43 shown in Figs. 6 and 7; and likewise has a longitudinal groove or slot 62 for receiving the disk 60. If desired, this disk 60 may carry a forwardly-extending arm 41', similar to the arm 41 shown in Figs. 6 and 7.

The method of operation is obvious: By means of hand-wheel 10, the desired package-chute is brought opposite the delivery-chute, whereupon the pawl 13 drops into engagement with the star-wheel 12; next the proper coin is inserted in the coin-hole 30 of the plunger, and the plunger shoved in; 105 as it travels inward, the upper surface of the coin serves as a bridge which sustains the forward arm of dog 31 (preventing the toe and the heel from locking the plunger), next the cam 43 trips dog 40 and ejects the coin; 110 the inner end of the plunger forces the arm 26 into engagement with the notch 19 (thereby locking the turntable rigidly), and thereafter the ejector 23—24 forces the lowermost package 14' rearwardly into the delivery-chute; and, finally, the plunger is withdrawn by the spring 15', ready for the next 115 customer.

I have thus described my invention fully and with considerable detail, but only for 125 the sake of clearness, since the invention is not limited to the precise constructions and arrangements set forth. My invention comprises (preferably in connection with the rotary plurality of package-chutes and 130

- means for actuating the same), a coin-carrying plunger for ejecting the lowermost package—a vertically-yielding ejector carried by said plunger—a dog having a toe and a heel
5 for preventing the plunger being pushed in except with the proper coin—means for ejecting the coin from the plunger—means for preventing the plunger from being pumped back and forth—and means actuated by the plunger for locking the package-chutes in position—besides the various combinations of the foregoing features, certain other features of construction and arrangement hereinafter set forth and claimed.
10 Having thus described my invention, I claim:
In a machine of the character set forth, the combination of a slidably mounted plunger having a coin receiving opening
20 therein and a smaller opening in the rear thereof, a spring actuated dog pivotally secured to the frame of the machine, said dog having at its front end a toe and a heel adapted to simultaneously enter the openings in the plunger, a double ended trip
25 dog pivotally mounted at its center on the frame and having the ends of its arms normally resting upon the upper surface of the plunger, a tripping cam formed upon and projecting above the upper surface of the 30 plunger and adapted for engagement with the rear arm of said last named dog, whereby the forward end of the same is adapted to be forced into the coin receiving opening of the plunger, said dogs being oppositely 35 located, one in advance of the other and arranged above the plunger, and means for automatically holding the plunger when forced inwardly and releasing the same when the coin is deposited from the plunger 40 thereby permitting the latter to assume its normal position.
In testimony whereof I have signed this specification in the presence of two subscribing witnesses.

FRED. C. WHITMORE.
